[57] ABSTRACT

Compensating circuit for voltage and temperature in a transistor circuit of complementary connection having an NPN type transistor and a PNP type transistor with its base connected to the collector of the NPN transistor. The voltage of the base of the NPN transistor is compared with the voltage of the emitter thereof so as to trigger the same so that the PNP transistor is triggered. The circuit comprises a first voltage dividing series circuit and a second voltage dividing series circuit. The first voltage dividing series circuit consists of a varistor diode and a resistor. The first series circuit is connected to the terminals of the electric source, so that the divided voltage of the varistor diode is applied to the emitter of the NPN transistor. The second voltage dividing series circuit consists of a varistor diode and a resistor. The second series circuit is connected to the terminals of the varistor diode of the first series circuit so that the divided voltage of the varistor diode of the second series circuit is applied between the base and the emitter of the NPN transistor. The variation in the voltage of the varistor diode in each of the first and the second series circuit due to the variation in the voltage of the electric source as well as the variation in the temperature is made small thereby permitting the NPN transistor to be stabilized.

COMPENSATING CIRCUIT FOR VOLTAGE AND TEMPERATURE IN A TRANSISTOR CIRCUIT

BACKGROUND OF THE INVENTION

The present invention relates to a compensating circuit for voltage and temperature in a transistor circuit, and more particularly, to a compensating circuit for voltage and temperature in a transistor circuit of complementary connection having an electric source, an NPN type transistor and a PNP type transistor with its base connected to the collector of the NPN transistor while the emitter of the PNP transistor is connected to one terminal of the electric source and the emitter of the NPN transistor is connected to the other terminal of the electric source, the voltage of the base of the NPN transistor being compared with that of the emitter thereof so as to trigger the same thereby permitting the PNP transistor to be triggered upon triggering of the NPN transistor.

It is desirable in a transistor circuit of the type described above to compensate for the variation in the voltage of the electric source as well as the variation in the temperature of the elements in the circuit so as to properly actuate the circuit.

The triggering of the PNP transistor in the above described transistor circuit might be delayed even though the NPN transistor is triggered, if the voltage of the base of the NPN transistor is made equal to or higher than the voltage of the emitter of the PNP transistor thereby resulting in an erroneous operation of the circuit.

The present invention solves the above problems.

The present invention is particularly useful for use in an electronic shutter disclosed in U.S. Pat. application Ser. No. 63,214, filed on Aug. 12, 1970, although the present invention is advantageously used with a conventional TTL type electronic shutter and other electronic appliances in which erroneous operation of the transistors therein due to the variation in the voltage of the electric source thereof and the variation in the temperature must be avoided so that they can be properly operated.

SUMMARY OF THE INVENTION

The object of the present invention is to provide a novel and useful compensating circuit for voltage and temperature in a transistor circuit of the type described above which solves the above problems.

The above object is achieved in accordance with the present invention by the provision of a first voltage dividing series circuit and a second voltage dividing series circuit in the transistor circuit, the first voltage dividing circuit having a varistor diode and a first resistor connected in series thereto with the first varistor diode connected to the one terminal of the electric source and with the first resistor connected to the other terminal of the electric source while the junction of the first varistor diode and the first resistor is connectable to the emitter of the NPN transistor through a switch so as to apply a voltage divided by the first varistor diode from the voltage of the electric source to the emitter of the NPN transistor, a relatively large current being flown through the first voltage dividing series circuit to thereby reduce the variation in the voltage applied to the emitter of the NPN transistor by the first varistor diode due to the variation in the voltage of the electric

source by virtue of the current-voltage characteristics of the varistor diode and the resistor in the voltage dividing series circuit, the second voltage dividing series circuit having a second varistor diode and a second resistor connected in series thereto with the second resistor connected to the one terminal of the electric source and with the second varistor diode connected to the junction of the first varistor diode and the first resistor while the junction of the second varistor diode and the second resistor is connectable to the base of the NPN transistor through a switch so that a voltage divided by the second varistor diode from the voltage of the first varistor diode is applied between the base and the emitter of the NPN transistor, the current flowing through the second voltage dividing series circuit being thus made relatively small thereby permitting the variation in the voltage of the second varistor diode due to the variation in the voltage of the electric source applied between the base and the emitter of the NPN transistor to be further reduced by virtue of the current-voltage characteristics of the varistor diode and the resistor in the voltage dividing series circuit so that the operation of the NPN transistor is stabilized. At the same time, the variation in the voltage of the first varistor diode due to the variation in the temperature applied to the emitter of the NPN transistor is made small with respect to the shifting of the current-voltage characteristics of a varistor diode per se due to the variation in the temperature by virtue of a relatively large current flowing through the first voltage dividing series circuit obtained by the current-voltage characteristics of the varistor diode and the resistor in the voltage dividing series circuit. The variation in the voltage of the second varistor diode due to the variation in the temperature which is applied between the base and the emitter of the NPN transistor is kept intermediate the shifting of the current-voltage characteristics of the varistor diode and the variation in the voltage applied to the emitter of the NPN transistor by the first varistor diode due to the variation in the temperature thereby permitting the variation in the triggering voltage between the base and the emitter of the NPN transistor due to the variation in the temperature to be compensated for by the variation in the voltage applied to the NPN transistor by the second varistor diode. Thus, the operation of the NPN transistor can be stabilized in a wide range of variation in the voltage of the electric source as well as in a wide range of variation in the temperature.

In the circuit described above, when the voltage appearing at the base of the NPN transistor is made equal to or higher than the voltage of the emitter of the PNP transistor, the PNP transistor is kept non-conductive until the voltage of the emitter of the NPN transistor is lowered with respect to the voltage of the emitter of the PNP transistor by the amount of the resultant voltage of the base-emitter voltage of the PNP transistor and the collector-emitter voltage of the NPN transistor even though the NPN transistor is triggered, because the voltage of the base of the PNP transistor is considered to be the same as the voltage of the base of the NPN transistor by virtue of the diode connection between the base and the collector of the NPN transistor, the voltage of the base of the NPN transistor being equal to or higher than the emitter of the PNP

transistor. Therefore, a time delay might occur in the triggering of the PNP transistor after the NPN transistor has been triggered, thus resulting in an erroneous operation of the circuit.

In accordance with a further feature of the present invention, a capacitor is provided in the circuit, one end of which is connected to the one terminal of the electric source while the other end is connected to the base of the NPN transistor. Thus, the capacitor is charged to a voltage appearing between the terminals of the second resistor in the second voltage dividing series circuit. The voltage thus charged in the capacitor is so determined that the voltage of the NPN transistor is lowered with respect to the voltage of the emitter of the PNP transistor by the amount of the voltage between the collector and the emitter of the NPN transistor. Since the triggering voltage between the base and the emitter of the NPN transistor is considered to be the same as the triggering voltage between the emitter and the base of the PNP transistor, they cancel each other so that the PNP transistor is triggered without delay upon triggering of the NPN transistor.

BRIEF DESCRIPTION OF THE DRAWINGS

FIG. 1 is a diagram showing the transistor circuit of the present invention;

FIG. 2 is a diagram showing the current-voltage characteristics of a varistor diode and a resistor connected in series thereto to form a varistor-resistor series circuit;

FIG. 3 is a diagram showing the variation in the current-voltage characteristics of the varistor diode and the resistor in the varistor-resistor series circuit due to the variation in the temperature; and

FIG. 4 is a diagram showing an electric circuit of an electric shutter in which the transistor circuit of the present invention is incorporated.

DETAILED DESCRIPTION OF THE PREFERRED EMBODIMENTS

Referring to FIG. 1, the transistor circuit of the present invention comprises an electric source, an NPN type transistor Tr_4 and a PNP type transistor Tr_5 . The collector of the transistor Tr_4 is connected to the base of the transistor Tr_5 , while the emitter of the transistor Tr_5 is connected to the plus terminal of the electric source, emitter of the transistor Tr_4 being connectable to the minus terminal of the electric source through a switch SW_4 , a resistor r and a switch SW_5 . The base of the transistor Tr_4 is selectively connectable through the switch SW_4 and the resistor r to the junction of a resistor and the collector of a transistor Tr_3 , the resistor being connected to the plus terminal of the electric source while the emitter of the transistor Tr_3 is connected to the minus terminal of the electric source. The transistor Tr_3 is incorporated in a preceding stage of the circuit such as an integrating circuit of an electronic shutter as described later, while the collector of the transistor Tr_5 is connected to the succeeding stage of the circuit such as a switching circuit of the electronic shutter described later. One end of a capacitor C_2 is connected to the plus terminal of the electric source at d , while the other end is connected to the base of the transistor Tr_4 at a . One end of a capacitor C_3 is connected to the plus terminal of the electric source while

the other end is connected to the emitter of the transistor Tr_4 . During the time the transistor Tr_3 is made conductive with the switch SW_5 held opened and the switch SW_4 switched to contact m , the capacitor C_2 is charged. The capacitor C_3 commences to be charged when the switch SW_4 is switched to contact n and the switch SW_5 is closed while the capacitor C_2 is maintained in the charged state. The voltage of the capacitor C_3 given at b to the emitter of the transistor Tr_4 is compared with the voltage of the capacitor C_2 at a given to the base of the transistor Tr_4 , so that, when the voltage between the base and the emitter of the transistor Tr_4 reaches the triggering voltage thereof, the transistor Tr_4 is rendered to be conductive so as to trigger the transistor Tr_5 .

The triggering of the transistor Tr_4 is affected by the variation in the voltage of the electric source as well as the variation in the temperature of the elements in the circuit, and further, the triggering of the transistor Tr_5 might be delayed after the triggering of the transistor Tr_4 depending upon the voltage of the base of the transistor Tr_4 with respect to the voltage of the emitter of the transistor Tr_5 as described previously.

In accordance with the present invention, a first voltage dividing series circuit consisting of a varistor diode D_B and a resistor R_o and a second voltage dividing series circuit consisting of a varistor diode D_A and a resistor r_o are provided. The varistor diode D_B is connected to the plus terminal of the electric source and the resistor R_o is connected to the minus terminal of the electric source, while the junction of the varistor diode D_B and the resistor R_o is connected through a switch SW_2 to the emitter of the transistor Tr_4 , so that a voltage divided by the varistor diode D_B is applied to the emitter of the transistor Tr_4 . The resistor r_o is connected to the plus terminal of the electric source and the varistor diode D_A is connected to the junction of the varistor diode D_B and the resistor R_o , while the junction of the varistor diode D_A and the resistor r_o is connected through a switch SW_1 to the base of the transistor Tr_4 , so that the voltage of the varistor diode D_A is applied between the base and the emitter of the transistor Tr_4 .

Assuming that the voltage in the forward direction of the varistor diode D_A is V_{FA} and the voltage in the forward direction of the varistor diode D_B is V_{FB} , the variation ΔV_{FB} in the voltage of the varistor diode D_B and the variation ΔV_{FA} in the voltage of the varistor diode D_A due to the variation in the voltage of the electric source from V_o to $V_o + \Delta V_o$ are expressed by $P_{10}P_{20}$ and A_oB_o , respectively, in FIG. 2.

Points P_1, P_2 in the curve P are the intersecting points with the characteristics of the resistor R_o in each of the varistor-resistor series circuits passing through point $V_o, V_o + \Delta V_o$, respectively, and points P_{10}, P_{20} are projections of the points P_1, P_2 on the abscissa of the diagram, points A, B being the intersecting points of the curve P with the characteristics of the resistor r_o in each of the varistor-resistor series circuits passing through the points P_{10}, P_{20} , respectively, while points A_o, B_o are the projections of the points A, B on the abscissa of the diagram, respectively.

Thus,

$$\Delta V_{FB} = P_{10}P_{20}$$

$$\Delta V_{FA} = A_oB_o$$

In FIG. 2, the curve P shows the current-voltage characteristics of the varistor diode and the straight lines V_o , P_1 , $V_o + \Delta V_o$, P_2 , P_{10} , A, P_{20} , B show the current-voltage characteristics of the resistor in the respective varistor-resistor series circuit, the resistor having the resistance R_o or r_o as shown.

Since a relatively large current flows through the varistor diode D_B and the $dP/dV > 0$ and $d^2P/dV^2 > 0$ as shown in FIG. 2, the value ΔV_{FB} is made very small in comparison with the variation ΔV_o of the voltage of the electric source. Drawing a line from point A in parallel to the abscissa of the diagram and designating the intersecting point thereof with the characteristics B P_{20} as D, then

$AD = P_{10}P_{20} = \Delta V_{FB}$,
and AD is greater than A_oB_o representing the value of ΔV_{FA} , because

$$dP/dV > 0$$

and the gradient of the characteristics B P_{20} is negative, i.e.,

$$\tan \alpha < 0.$$

Thus,

$$AD > A_oB_o = \Delta V_{FA}$$

Therefore,

$$\Delta V_o > \Delta V_{FB} > \Delta V_{FA}$$

Thus, the variation in the voltage of the varistor diode D_A applied between the base and the emitter of the transistor Tr_4 is made very small so that the transistor Tr_4 is adequately stabilized with respect to the variation in the voltage of the electric source.

Referring to FIG. 3, the curves P and Q show the forward current-voltage characteristics of the varistor diode at the temperature T and the temperature $T + \Delta T$, respectively. As shown, the curve Q is shifted from the curve P by the value of $\Delta V(T)$. The variation in the voltage ΔV_{FB} of the varistor diode D_B due to the variation ΔT in the temperature T is shown by P_oQ_o , points P_1 , Q_1 being the intersecting points of the characteristics of the resistor R_o of the varistor-resistor series circuit with the curves P, Q, respectively, while points P_o , Q_o are the projections of the points P_1 , Q_1 on the abscissa. Since the current flowing through the varistor diode D_B is relatively large, the value ΔV_{FB} is made small.

Therefore,

$$\Delta V(T) > \Delta V_{FB}$$

The variation in the voltage ΔV_{FA} of the varistor diode D_A is expressed by the horizontal distance between point A and point B, the point A being the intersecting point of the curve P with the characteristics of the resistor r_o in the varistor-resistor series circuit passing through the point P_o , while the point B is the intersecting point of the curve Q with the characteristics of the resistor r_o in the varistor-resistor series circuit passing through the point Q_o .

Curve Q' shows the characteristics of the varistor diode which is shifted from the curve P by the amount of ΔV_{FB} . Drawing a line from the point A in parallel to the abscissa and designating the intersecting point with the curve Q' and the intersecting point with the curve Q as F and D, respectively.

Then,

$$AF = P_oQ_o = \Delta V_{FB}$$

$$AD = \Delta V(T)$$

Since dQ/dV of the curve Q is positive, i.e.,

$$dQ/dV > 0$$

and the gradient of the characteristics of the resistor r_o in the varistor-resistor series circuit is negative, projection of the point B on the line AD falls intermediate the points F and the point D.

Thus,

$$VF(T) = AD > \Delta V_{FA} > AF = \Delta V_{FB}$$

Therefore, the variation ΔV_{FA} in the voltage of the varistor diode D_A due to the variation in the temperature is kept smaller than $\Delta V(T)$ although it is greater than the value of ΔV_{FB} .

The variation in the voltage of the varistor diode D_A due to the variation in the temperature is considered to be the same as that of the transistor Tr_4 as the forward current of the varistor diode D_A is reduced so that both act to cancel each other in the circuit. Since the current flowing through the varistor diode D_A is small, the operation of the transistor Tr_4 is stabilized even though the temperature varies.

The temperature characteristics of a transistor is, for example, 2.2 mV/oC while the temperature characteristics of a varistor diode is, for example, 1.8 mV/oC.

In accordance with a further feature of the present invention, the resistance of the resistor r_o in the second voltage dividing series circuit is so determined that the voltage of the capacitor C_2 charged in accordance with the voltage appearing between the terminals of the resistor r_o is effective to lower the voltage of the base of the transistor Tr_4 by the amount of the collector-emitter voltage of the transistor Tr_4 with respect to the voltage appearing at the emitter of the transistor Tr_5 . Thus, the transistor Tr_5 is triggered without delay upon the triggering of the transistor Tr_4 for the reason previously described.

FIG. 4 shows an electric circuit of an electronic shutter in which the transistor circuit of the present invention is incorporated. Such an electric circuit is disclosed in the aforementioned U.S. Pat. application.

Briefly, the electric circuit shown in FIG. 4 comprises an integrating circuit consisting of a photoelectric element R for receiving the light from the object through an objective of the camera incorporating the shutter, a capacitor C_1 connected in series to the photoelectric element R to form a timing circuit for determining a reference time in accordance with the intensity of light from the object and transistors Tr_1 , Tr_2 and Tr_3 which are triggered after the expiration of the reference time, a memory circuit consisting of an electrical element r such as a photoelectric element for receiving the light from the object directly or a resistor, the above described capacitor C_2 selectively connectable to the electrical element r through a switch SW_4 to form a timing circuit and the above described NPN type transistor Tr_4 , an exposure control circuit consisting of the capacitor C_3 selectively connectable to the electrical element r by switching the switch SW_4 to form a timing circuit and the transistor Tr_5 , and a switching circuit consisting of transistors Tr_6 , Tr_7 and Tr_8 and an electromagnet M for maintaining shutter blades opened when energized, resistors and switches being incorporated as shown for properly actuating the shutter.

In accordance with the present invention, the first voltage dividing series circuit consisting of the varistor diode D_B and the resistor R_o and the second voltage dividing series circuit consisting of the varistor diode D_A and the resistor r_o are connected in the circuit as shown.

In operation, the switch SW_0 is first closed in the first stage of the operation of a release means in the camera to render the transistor Tr_8 to be conductive so as to be ready for preventing the trailing shutter blade from being closed by means of the electromagnet M. Then, switches SW_1 and SW_2 are closed during the operation of the release means to apply the divided voltage of the varistor diode D_A between the base and the emitter of the transistor Tr_4 while the capacitor C_2 is charged to obtain the voltage appearing at the terminals of the voltage dividing resistor r_0 . Then, the switch SW_3 is closed after the switches SW_1 and SW_2 have been opened so that the integrating circuit is made operative thereby making the transistors Tr_1 , Tr_2 non-conductive while the transistor Tr_3 is made conductive during the reference time set by the capacitor C_1 and the photoelectric element R in accordance with the intensity of light from the object. During the time the transistor Tr_3 is conductive, the capacitor C_2 is charged through the electrical element r so that a reference voltage including the divided voltage previously given is set in the capacitor C_2 in accordance with the intensity of light from the object.

Upon further operation of the release means, the switch SW_4 is switched to contact n while the switch SW_5 is closed in coupled relationship with the opening of the leading shutter blade, the trailing shutter blade being prevented from being closed by the electromagnet M. Thus, the capacitor C_3 is charged through the electrical element r , so that the reference voltage applied to the base of the transistor Tr_4 is compared with the voltage given to the emitter of the transistor Tr_4 thereby permitting the same to be triggered when the voltage between the base and the emitter of the transistor Tr_4 reaches the triggering voltage thereof. When the transistor Tr_4 is triggered, the transistors Tr_5 , Tr_6 and Tr_7 are made conductive while the transistor Tr_8 is rendered to be non-conductive, so that the electromagnet M is deenergized to close the trailing shutter blade thereby permitting the proper exposure to be obtained in accordance with the intensity of light from the object.

As previously described, the base-emitter voltage of the transistor Tr_4 is compensated for variation in the voltage of the electric source and the variation in the temperature in accordance with the present invention. Thus, proper operation of the shutter is insured.

One or more amplifying stages of the PNP transistors may be added to the transistor Tr_5 . In this case, the voltage of the base of the transistor Tr_4 is lowered with respect to the voltage of the emitter of the transistor of the last stage by the resultant of the collector-emitter voltage of the transistor Tr_4 and the base-emitter voltage of the PNP transistor multiplied by the number of the amplifying stages added.

I claim:

1. Compensating circuit for voltage and temperature in a transistor circuit of a complementary connection having an electric source, an NPN type transistor and PNP type transistor, conductive means for connecting the base of said NPN type transistor and the collector of said PNP type transistor to preceding and succeeding stages of said circuit respectively, the collector of said NPN type transistor being connected to the base of said PNP type transistor with the emitter of said PNP type transistor connected to one terminal of said electric source while the emitter of said NPN type transistor is connected to the other terminal of said electric source for comparing the voltage of the base of said NPN type transistor with that of the emitter thereof so as to trigger the same, thereby permitting said PNP type transistor to be triggered, wherein the improvement comprises a first voltage dividing series circuit consisting of a first varistor diode and a first resistor connected in series thereto with said varistor diode connected to said one terminal of said electric source and with said first resistor connected to said other terminal of said electric source while the junction of said first varistor diode and said first resistor is connectable to the emitter of said NPN type transistor through a switch, and a second voltage dividing series circuit consisting of a second varistor diode and a second resistor connected in series thereto with said second resistor connected to said one terminal of said electric source and with said second varistor diode connected to the junction of said first varistor diode and said first resistor, the junction of said second varistor diode and said second resistor being connectable to the base of said NPN type transistor through a switch, thereby permitting the voltage between the base and the emitter of said NPN type transistor to be compensated for with respect to both the variation in the voltage of said electric source and the variation in the temperature by virtue of said first and said second varistor diodes.
2. Compensating circuit according to claim 1, wherein the improvement further comprises a capacitor with one end thereof connected to said one terminal of said electric source and with the other end connected to the base of said NPN type transistor thereby permitting said capacitor to be charged to the voltage between the terminals of said second resistor in said second voltage dividing series circuit, the voltage of said capacitor thus charged being so determined that the voltage of the base of said NPN type transistor is lowered with respect to the voltage of the emitter of said PNP type transistor by the voltage between the collector and the emitter of said NPN type transistor, thereby permitting said PNP type transistor to be triggered without delay upon triggering of said NPN type transistor.

* * * * *
